UNITED STATES PATENT OFFICE

MICHAEL SMITH, OF MODESTO, CALIFORNIA

PNEUMATIC ROCK DRILL

Application filed August 14, 1924. Serial No. 732,123.

This invention relates to pneumatic drills and hammers in general and more particularly to a rock drill in which the drilling is accomplished by successive blows upon the 5 drill steel and the steel is also given a rotary motion between striking impacts against the rock.

The principal objects of my improvements are to overcome some of the well known faults 10 of prior drills of this class in providing:

A—Automatic means for instantly reducing the force of the blow upon the tool upon entering soft earth or a pocket in the rock, thus avoiding destructive blows against the 15 parts when not opposed by the resistance of the rock.

B—A manual or automatic control for reducing the force of the working blow without affecting other operations of the mechanism. 20

C—A simplified rotating drive for giving the drill steel a fractional turn, operative upon either stroke of the piston.

D—A manual control to stop the rotation 25 without affecting the drilling operations.

E—An improved arrangement for blowing out the drill hole through the water line.

F—An improved method of packing the water tube within the anvil block. 30

G—An improved method of packing the anvil housing.

H—An improved piston construction whereby various weights of piston may be used as the work may require, yet without 35 affecting the cut-off relation of the parts.

I—Minor constructional improvements which will appear as the description proceeds.

I attain the objects mentioned by the pneumatic drill construction shown in the accompanying drawings and in which Figure 1 is a longitudinal section through the operating mechanism showing all of the important features, and Figure 2 is a cross section of Figure 1 taken along the line 2—2. Figure 3 shows in enlarged section my special ring packing. Figure 4 is a sectional view of a valve employed in my device showing its relation to certain passageways. 45

50 Before entering a detailed description of

the mechanism, attention is called to the fact that the assemblage consists essentially of a main cylinder in the axial line of the drill steel or tool having the usual reciprocating piston or hammer within it for delivering 55 successive blows to the tool, and of a plurality of other cylinders, with pistons or valves therein for controlling the operation of the mechanism and also for rotating the tool.

These auxiliary cylinders and valves are 60 in practice positioned around the main cylinder in a way to facilitate construction and assemblage of the mechanism, also to provide for the most direct running of the various air passages and for coring them in the solid 65 metal of the body to avoid exposed piping as much as possible.

In the drawing, however, the relation of the parts mentioned has been altered, the proportions of the walls changed, also the run of 70 ports, so as to bring the various features into one comprehensive cooperating assemblage and avoid reference to many sectional views in additional drawings.

In the figures, (1) is the body of the machine comprising several sections all held together by the usual clamping bolts extending through suitable flanges (2) and engaging the head (3). Within the body is the main cylinder (4) with a reciprocating piston (5) therein. 75

Axially extending from the body is the drill steel or tool (6) which may be lugged as shown at (7) or not.

The tool is here shown as having a hollow shank aligned over a water tube (8) extending from the head through the piston and passing through an anvil block (9) which is 85 slideable on the tube and which block is slideable within the anvil housing (10).

The tube is packed within the anvil block by means of a special silk ring packing (11) forced through the tapered recess (12) to a slightly enlarged recess (13), but the piston is slideable on the tube without any packing. 90

The anvil has a shoulder (14) to limit its inward sliding and in operation of the drill is held tightly against this shoulder by the endwise pressure of the tool which rests upon it as shown. This anvil also functions as an 100

automatic valve to prevent a blow being delivered to the tool if the latter finds no resistance against the rock on account of penetrating a pocket therein or of entering soft earth, for in either case the pressure of the tool upon the anvil is reduced whereupon the anvil is forced outward by the operating air and trips a premature exhaust on the striking blow as will later be described.

10 The main piston or hammer (5) is a plain steel cylinder adapted to cover and uncover the air ports for automatic reciprocation and has a central chamber filled with wood (15) or lighter metal so as to provide for internal change of similar length pistons with larger or smaller wool filled chambers (15') and whereby the weight of the piston can be suited to the work without altering the relation of the air ports to the piston's length. The 15 wood filler has also been found a valuable oil retainer to insure permanent lubrication of the water tube (8).

15 The reciprocation of the piston (5) is controlled by the distributing valve (15) which alternately admits air under pressure from the main inlet port (16) to the ports (17) and (18) extending respectively to opposite ends of the piston, and which ports alternately act as exhausts for their respective ends by 20 communicating through the recessed valve with a common exhaust port (19).

25 It should be here noted that the various air passages are cored in the metal of the body and unless shown as connecting at intersecting points they are in different planes so as to pass each other and lead to their various destinations without interference.

30 The valve (15) is itself tripped back and forth by the uncovering by the piston of small ports (20) and (21) which convey some of the active pressure fluid to the ends of the valve somewhat before the end of the stroke of the hammer piston in either direction.

35 Upon the inward or return stroke of the piston (5) the air reacts against the anvil housing (10) as well as the end of the anvil block (9) held back by the drill tool through pressure of the tool end against the rock being drilled, but in case of striking a pocket in the rock, or if for any other reason the pressure of the tool against the anvil is relieved, the anvil is at once forced outward by the air pressure acting against its inner end, carrying the tool with it and bringing 40 the by pass duct (22) into registry with the automatic hammer blow control valve passage (23) which results in instantly reducing the force of the blow of the hammer piston (5) so that it will not strike with full force 45 against an inoperative tool to batter its lugs or destroy the mechanism, but will keep up a gentle blow in soft material.

50 This is accomplished by a small piston valve (24) normally forced away from the head (3) by a spring (25) to close off an aux-

iliary reverse valve tripping port (26) which communicates with the valve tripping passage (21).

55 This small valve (24) is displaced by active air pressure from the by pass (22) through the passage (27) upon relief of the tool pressure on the anvil and opens auxiliary reversing port (26) so that the force of the hammer blow of piston (5) is diminished at about the first third of its travel and this condition is maintained until the pressure on the drilling tool is restored.

60 A check valve (28) is placed in passage (27) and a slow leak at (29) to permit return of valve (24) upon reestablishing normal drilling conditions.

65 The shock of distributing valve (15) is broken largely through confined air by proper design of port areas and further by metal plates (30) backed by live rubber disks (31).

70 In addition to the main cylinder exhausting alternately through its intake ports as explained, an additional or final exhaust is provided at (32) uncovered at either end of complete stroke.

75 When drilling in material not requiring the maximum blow, the air pressure inlet (18) for the striking blow may be independently throttled to any predetermined degree by means of a thumb control button (33) actuating a spring released plunger (34) which closes off the inlet passage (18) to an amount depending on the threaded adjustment of the plunger with respect to the button (33), which adjustment is permitted by the slotted end of the threaded member as shown at (35), thus by a simple pressure of the thumb the force of the blow is instantly reduced.

80 The water tube receives its supply through the passage (36) from hose (37) controlled by valve (38) and the drill may be blown with air by a simple pressure of thumb piece (39) which moves the spring returned plunger valve (40) and opens the by pass duct (41) to the main air inlet (16) so that the air can pass directly to the water tube. The main air hose is indicated at (42) with main valve at (43).

85 The water tube (8) is sealed in the head (3) and ported to passage (36) by suitable packing and glands in any suitable manner as indicated.

90 Intermittent partial rotation of the drill tool is effected through means of a ratchet and pawl arrangement similar to the one described in my former Patent No. 1,284,804, with the exception that the reciprocating wedge (44) is operated by an air piston (45) which is thrown outward at each inward movement of the main piston (5) by air received at the same time through a passage (46) connecting with air inlet (17). Or if desired the rotation may be effected at the outward stroke of the piston by throwing the two way valve (69)

to connect the passage (46) with the passage (70) and thereby with the live air passage (18) at a point in advance of the choke plunger (34).

5 This passage (46) enters piston (45) through a cut-off slot (46) in the side thereof and having an extension (47) to the end of the piston so that the pressure can act against a rubber pad (48) placed at the end of the 10 piston cylinder (49) against the head (3).

The pad serves to take the shock of the return effected by spring (50) surrounding the piston rod (51) and reacting against the body (1). At the return stroke the air 15 exhausts to the main cylinder through port (52) uncovered by the main piston (5) at the end of its inward travel and thence through the passages (17) and (32), and the air above the piston escapes to a certain extent through 20 the joints around the wedge operating mechanism thereby diffusing oil throughout, while the remainder is entrapped as a cushion until scavenged by uncovering of port (53) by the main piston (5).

25 The piston (45) is also filled with a block of wood (45') so that it may still have length and area yet be light in weight.

Rotary movement is transmitted to the tool (6) through its lugs (7) engaging slots (54) 30 in retaining nut (55) screwed into the revolvable ratchet hub (56) having ratchet teeth (57) engaged by pawl (58) pivoted to sliding pawl block (59) and forced toward the teeth by springs (60), the pawl block being moved 35 by the piston wedge (44) to advance the pawl block against spring (61) at each stroke of the piston (45) substantially as described in my former patent mentioned.

To avoid displacement or binding of piston 40 rod (51) through wear of the wedge (44) or block (59) a locking though sliding joint (62) is provided to connect the piston rod to the wedge.

45 By the arrangement shown it will be seen that the rotation of the tool takes place only before the blow of piston (5) and that the tool is stationary at the moment of the blow of the piston.

50 At any time that it is desired to drill without rotation of the tool, a pressure of the finger on the push button (63) projects the end of it within the cylinder (49) and stops the piston. It should be observed that this button (63) is at a portion of the cylinder circumference to avoid cut off slot (46).

In operation should the tool break through and allow the anvil (9) to move forward upon the impact of piston (5), the blow is arrested 60 by a steel ring (64) supported against one of my special silk packing rings (65).

A similar packing ring is placed at (66) to seal the anvil housing (10) against the revolvable ratchet hub (56). This packing was devised especially for this purpose where a seal must be maintained and the material must

not compress and become dead when subjected to the force of an occasional wild blow when the tool breaks through.

Figure 3 is an enlarged section of the packing rings and shows them as made of silk threads wound around (on a mandrel) in layers slightly crossing one another as shown at (67) to form a ring, then winding or sewing other silk threads through the opening of the ring and over the outer sides as shown at (68) to tie them all together. These special silk rings are soaked in oil before placing in position in the machine, ring (18) being forced into place with a special tool.

Having thus described in detail my improved rock drill it will be seen to possess valuable features useful also in similar tools such as air hammers and the like, especially the automatic reduction of the striking blow upon reducing endwise pressure of the tool 65 upon the work, and while I show this accomplished by displacement of an anvil block whereby the reversing valve is prematurely tripped by air pressure, it is manifest that this may be carried out by quite a number of artifices and any arrangement which will produce this result falling within the spirit of my invention is sought to be covered in my appended claims.

I claim:

1. In a pneumatic rock drill, a cylinder, a piston movable therein, means for automatically admitting fluid under pressure into the ends of said cylinder for reciprocating the piston, auxiliary means for reversing the movement of the piston when the latter has covered only a portion of its stroke, and tool controlled means for making operative said auxiliary means upon excessive outward movement of the tool.

2. In a pneumatic rock drill, a cylinder, a piston movable therein, means for automatically admitting fluid under pressure into the ends of said cylinder for reciprocating the piston, auxiliary fluid operated means for reversing the movement of the piston when the latter has covered only a portion of its stroke, a tool, and tool controlled means for making operative said auxiliary means upon excessive outward movement of the tool, said tool controlled means comprising an anvil block movably disposed between the piston and the tool and having a fluid passageway placing the fluid in the cylinder in communication with the piston reversing means when the anvil is moved to a predetermined position.

3. In a pneumatic rock drill, a cylinder, a piston movable therein, means for automatically admitting fluid under pressure into the ends of said cylinder for reciprocating the piston, auxiliary means for reversing the movement of the piston when the latter has covered only a portion of its stroke, and tool controlled means for making operative said

- auxiliary means upon excessive outward movement of the tool, said auxiliary means comprising an auxiliary valve actuated when the tool controlled means is actuated, said auxiliary valve when actuated causing said first named means to cut off the fluid to the piston on its power stroke during the initial movement of the piston for diminishing the force of its blow.
4. A pneumatic rock drill comprising a cylinder, a piston movable therein, said cylinder having fluid passages for admitting fluid under pressure for reciprocating the piston, a valve for alternately admitting fluid to the ends of the cylinder, an auxiliary valve for admitting fluid to the first valve for actuating it after the piston has covered only a portion of its stroke, said first valve when thus actuated admitting fluid to the piston for reversing its movement, whereby the piston will deliver a light stroke to a tool.
5. A pneumatic rock drill comprising a cylinder, a piston movable therein, said cylinder having fluid passages for admitting fluid under pressure for reciprocating the piston, a valve for alternately admitting fluid to the ends of the cylinder, an auxiliary valve for admitting fluid to the first valve for actuating it after the piston has covered only a portion of its stroke, said first valve when thus actuated admitting fluid to the piston for reversing its movement, whereby the piston will deliver a light stroke to a tool, and tool controlled means for operating said auxiliary valve.

MICHAEL SMITH.
